INVENTOR
HARRY C. MALLORY
BY *John E. Hubbard*
ATTORNEY

UNITED STATES PATENT OFFICE.

HARRY C. MALLORY, OF NEW YORK, N. Y.; SUE R. MALLORY ADMINISTRATRIX
OF SAID HARRY C. MALLORY, DECEASED.

ENGINE-COOLING SYSTEM.

Application filed July 8, 1921. Serial No. 483,202.

My present invention comprises improvements in that type of engine cooling system especially adapted for use with automobile and analogous internal combustion engines 5 in which all or practically all of the heat abstracted from the engine by the cooling liquid is normally utilized in vaporizing the cooling liquid and is dissipated in a condenser in which the vapor is condensed, with 10 provisions for regulating the capacity of the condenser as required to thereby maintain a constant vapor pressure in the system and a constant temperature of the liquid leaving the jacket.

15 The general object of the present invention is to provide improved apparatus for the purpose specified characterized in particular by the simple and effective provisions made for maintaining a forced circulation of 20 the cooling liquid through the jacket under varying conditions of use, for separating the vapors formed from the unvaporized liquid passing through the jacket and condensing said vapors, and for maintaining in the system 25 cooling liquid in variable excess over the minimum required for the operation of the system.

The various features of novelty which characterize my invention are pointed out 30 with particularity in the claims annexed to and forming a part of this specification. For a better understanding of the invention, however, and the advantages possessed by it reference should be had to the accompanying 35 drawings and descriptive matter in which I have illustrated and described a preferred embodiment of my invention.

Of the drawings:

Fig. 1 is an elevation with parts broken 40 away and in section of an automobile engine equipped with my improved cooling system; and

Fig. 2 is a section through the condenser portion of Fig. 1.

45 In the embodiment of my invention illustrated in the drawings, A represents the cooling liquid jacket for the cylinder A⁵ of an ordinary internal combustion automobile engine. An inlet A' is provided at the bottom 50 of the jacket space for the cooling liquid which will ordinarily be water or a water and alcohol mixture, and A² represents an upper outlet from the jacket. In the particular construction shown the outlet A² opens from the end of the jacket space near its top 55 and is of substantial size. The outlet A² is connected by piping C to a condenser B which may be similar in construction and arrangement to the ordinary radiator employed on a water cooled automobile engine. 60 The piping C comprises an upper branch C' opening to the top chamber B² of the condenser and a lower branch C² running to the bottom header or hot well B³ of the condenser to which it preferably opens at the under side 65 so that the passage through the branch C² is water sealed at its lower end. Flexible couplings C⁸ are shown as included in the piping branches C' and C². Interposed between the upper chamber B² and hot well B³ of the 70 condenser B are a group of condensing surfaces shown as formed by small open ended horizontal tubes B' having their ends expanded and connected together to provide end walls closing the ends of the intertube 75 space. Advantageously the piping C has its vapor outlet C² connected to the chamber B² at a level appreciably above the normal water level in the system which in the construction shown is located just above the bottom 80 of the outlet A² from the jacket. Liquid of condensation formed in the condenser, and unvaporized liquid entering the bottom chamber B³ of the latter through the branch C² are passed to the water inlet A' of the 85 jacket by a conduit D including a pump E. Advantageously in some cases the conduit D is formed as shown with a goose neck portion D' extending to the water level which it is desired to maintain in the jacket so as 90 to prevent the jacket from draining when the pump is stopped. To prevent siphon draining the goose neck should be vented as by means of the vapor equalizing connection F from the top of the goose neck into the 95 condenser B. The pump E is driven, in the construction shown, from the engine shaft through a reduction gear conventionally illustrated at E' and through which the driving belt G for the fan G' is also driven. 100

- Preferably provisions are made for admitting air to and withdrawing air from the condenser as disclosed in my prior Patent No. 1,424,664, August 1, 1922, and in my prior 5 application, Serial No. 473,439, filed May 28, 1921, and to thereby vary the capacity of the condenser as required to maintain an approximately constant vapor pressure and temperature in the condenser notwithstanding 10 variations of engine load and in the temperature of the external atmosphere. The means shown for this purpose comprises an air pipe H connected through a steam trap I to the suction intake manifold of the engine to thereby exhaust air from the condenser as required to maintain a minus pressure 15 therein. As shown the pipe H projects through the condenser and is closed at its front and is formed with an air inlet H' at its under side through which air may enter 20 from the intertube space but into which water of condensation draining down from the condensing tubes B' will not fall. The minus pressure thus maintained is fixed by the adjustment of a vacuum relief valve K which 25 automatically opens to admit air to the condenser when the pressure of the atmosphere exceeds the pressure in the condenser by a predetermined amount.
- 30 In the preferred contemplated mode of use of the apparatus shown in the drawings, the pump E passes water into the jacket at a rate appreciably in excess of the rate of evaporation, and the vapor formed in the jacket and the unvaporized portion of the liquid both pass out of the jacket through the outlet A² into the piping C from which the vapor passes into the condenser chamber B² through the branch pipe C', while the unvaporized liquid passes into the hot well or 35 bottom chamber of the condenser through the branch C², entering the latter without appreciable cooling. If desired the piping C, and particularly branch C², and the hot well walls may be insulated against heat 40 losses thus facilitating the operation of the engine, and particularly the starting of the engine, in cold weather as well as reducing the danger of trouble from freezing. The hot well B² is advantageously proportioned 45 to hold a considerable amount of water, and the water thus stored in the system is in excess of that required for regular operation, and reduces the frequency with which water 50 must be added to the system to make up for liquid and vapor losses. O represents a connection through which the system may be charged with cooling liquid and O' represents a cap normally closing this connection.
- 55 In the preferred construction and mode of operation contemplated, a free vapor space 60 is maintained in the upper portion of the engine jacket into which all or the major portion of the vapor liberated in the system initially passes. The apparatus will operate
- satisfactorily, however, under conditions in which the upper end of the pipe C² and consequently the water level in the system is above the top of the jacket as may be necessary with some types of engines or conditions 70 of use. In such cases all or a large portion of the vapor is liberated in the piping C. The apparatus will still function indeed under conditions in which from time to time considerable quantities of unvaporized liquid 75 pass into the top of the condenser. The described provisions for admitting air to, and withdrawing air from the condenser so as to maintain a constant pressure in the latter insures an approximately constant water 80 temperature at the top of the jacket.
- With the apparatus disclosed I obtain the advantages of a continuous forced circulation of liquid through the jacket coupled with the temperature control and heat dissipating 85 capacity characteristic of a cooling system in which the heat dissipated is wholly or mainly latent heat of evaporation liberated in the condenser, and with a capacity for holding a considerable amount of liquid in 90 excess of that required for intended operation. The invention is adapted for use with many existing types of engines without material changes in the engine structures.
- While in accordance with the provisions 95 of the statutes I have illustrated and described the best forms of my present invention now known to me, it will be apparent to those skilled in the art that changes may be made in the form of my invention without departing from the spirit of my invention as set forth in the appended claims, and that certain features of my invention may sometimes be used to advantage without a corresponding use of other features.
- Having now described my invention, what I claim as new and desire to secure by Letters Patent, is:
1. In an engine cooling system, the combination with an engine jacket having an upper outlet, of a condenser forming the main heat dissipating element of the system and having a hot well for liquid of condensation at its lower end, a connection from the jacket to the condenser providing a free vapor path 110 from said outlet to the top of the condenser and a water sealed path of flow for liquid from said outlet to the hot well of the condenser, means for passing liquid from the condenser hot well into the jacket at a rate 115 exceeding that at which liquid is vaporized by the heat absorbed in the jacket.
  2. In an engine cooling system, the combination with an engine jacket having an upper outlet, of a condenser forming the main heat dissipating element of the system and having a hot well for liquid of condensation at its lower end, of a connection from the jacket to the condenser, providing a free path 120 from said outlet to the top of the condenser

and a water sealed path of flow for liquid from said outlet to the hot well of the condenser, means for passing liquid from the condenser hot well to the bottom of the jacket at a rate exceeding that at which liquid is vaporized by the heat absorbed in the jacket, and means for regulating the condenser ca-

pacity as required to maintain an approximately constant pressure therein.

Signed at New York in the county of New ¹⁰ York and State of New York this 7th day of July A. D. 1921:

HARRY C. MALLORY.
